UNITED STATES PATENT OFFICE

CHARLES E. HANNY, OF UNIONVILLE, CONNECTICUT, ASSIGNOR TO TRUMBULL ELECTRIC MANUFACTURING COMPANY, OF PLAINVILLE, CONNECTICUT, A CORPORATION OF CONNECTICUT

INCLOSED SWITCH

Application filed January 3, 1928. Serial No. 244,228. 10

My invention relates to what are commonly termed "inclosed or safety switches". The main object is to provide a simple and reliable construction which may be readily installed and replaced.

5 A special object is to provide a construction in which the switch mechanism per se is so constructed and assembled separately from the inclosing case that it may readily be inserted into or removed from the switch box.

In installations of this character the switch box is usually mounted on the wall and the conductors are run in conduits which are secured to the box. In attaching conduits or 15 other wire conducting devices to the box, it is desirable to have as much unobstructed working space inside of the box as possible in order that the wireman may have ample space for properly making the mechanical connections and for drawing the wires through the conduits into the box. Sometimes the switch mechanism is disabled in some way and it becomes necessary to repair or replace it. Where the installation is constantly in use it 20 is essential that the service be interrupted as little as possible. It is, therefore, important to facilitate the original installation and the subsequent repair or replacement as much as possible.

30 I accordingly provide an inclosed switch in which the switch per se may be entirely removed from the box after which the conduits may be attached in any suitable manner. After the conduits are secured in position, the 35 wires may be drawn through them and cut to the proper length ready to be secured to the terminals of the switch which may now be installed in the box. This box, as is usual, opens at the front and is provided with a 40 hinged cover. The side of the box opposite the hinge is cut away for a considerable area.

The switch mechanism itself may be of any suitable type but is preferably of the type disclosed, for instance, in the Getchell Patents 45 1,534,515 and 1,534,517. The switch mechanism is mounted on a supporting frame or carrier member which is preferably constructed from a single piece of sheet metal and formed with a bottom plate and a side 50 plate. The switch per se is secured to the

bottom plate and the switch operating mechanism and handle are mounted on the side plate. This switch operating mechanism preferably includes a quick break mechanism of a suitable type. The side plate is also 55 preferably provided with interlocking mechanism similar to that disclosed in the Sutherland Patent 1,288,740 and Knudsen Patent 1,310,163 for holding the cover closed when the switch is closed and for preventing the closing of the switch when the cover is open. The switch frame is adapted to be readily interlocked with the switch box and held securely by two screws, the side plate of the frame closing the opening in the side of the box.

Fig. 1 is a perspective view of an inclosed switch embodying one form of the improvements of my invention, the cover of the box being closed and the handle being in the On position.

Fig. 2 is a front view of the switch in the Off position, the cover being open.

Fig. 3 is a side view of the operating mechanism and its supporting frame.

Fig. 4 is a transverse sectional view of the 75 casing showing an end view of the switch and operating mechanism in the On or closed circuit position.

Fig. 5 is an end view of the switch and its supporting frame, the parts being in the Off or open circuit position.

Fig. 6 is a view showing a cross section of the box with the cover open and the switch and its actuating mechanism about to be inserted or removed.

Fig. 7 is a perspective view showing the box, the switch and its supporting frame separated.

The box 10 may be of any suitable character and provided with any suitable form of knock-outs or other means for securing cables or conduits in place. The cover 11 is preferably hinged at 12 in any suitable manner. This box is also preferably provided with a suitable latch 13 provided with means for facilitating sealing or locking of the box.

Any suitable form of switch mechanism may be provided. It preferably has an insulating base 14 and a crank pin 15 pivoted to swing about the hub 16 of the switch member.

so as to move the switch member or members to the On or Off position in any suitable manner.

The frame or carrier has a back plate 17 and a side plate 18 preferably formed of a single piece of sheet metal. The switch is secured to the back plate 17 in any suitable manner, as for instance, by means of screws 19. The back plate is provided with a tongue 20 adapted to fit in a slot or recess 21 in the rear corner of the box. The side 22 of the box opposite the hinges 12 is cut away at 23 throughout an area somewhat smaller than the area of the side plate 18 of the carrier frame and provided with notches 24 and 25 to receive the shanks of the screws 26 and 27, respectively. This permits the carrier frame to be readily inserted, as shown in Fig. 6, that is, the tongue 20 is inserted in the slot 21 with the switch and its carrier frame inclined. The right hand edge of the switch carrier frame is then pushed back or down into the box until the shanks of the screws fit into the notches 24 and 25. The screws are then tightened to hold the switch and carrier frame in place. The side plates 18 and 22 may also be provided with interlocking catch members 28 and 29 to prevent their relative accidental movement when the screws are loose. The switch actuating mechanism in the preferred form consists of a handle 30 which is mounted in the side of the plate 18 so as to rotate and provided with a cam plate 31 on the inside adapted to interlock with the latch member 32 which is pivoted and spring pressed so as to interlock with the pin or projection 33 on the cover when the box is closed and the switch is On. When the switch is Off the latch 32 is released so that the movement of the cover pin 33 is unobstructed. The plate 34 has a lost motion connection with the handle 30 and has two arms for engaging the crank pin 15 of the switch. This plate 34 also has an arm 35 which is under pressure of the spring 36 which tends to hold the plate 34 in the position shown in Fig. 3 when the switch is Off and in a position 180 degrees revolved from the position of Fig. 3 when the switch is On. This spring and plate 34 constitute the quick make and break or snap action of the switch.

When installing the apparatus the cover is opened and the screws 26 and 27 are loosened and the entire switch is removed from the box, thus entirely clearing the inside of the box for the mechanical operations of attaching the necessary conduits or other fittings. The large opening 23 greatly facilitates this part of the work. After the conduits are secured in position and the wires drawn in the switch may be secured in position and the ends of the wires secured to their respective switch terminals.

In case a repair is necessary, it is simply necessary to throw the switch to the Off

position, disconnect the circuit wires, loosen the screws 26 and 27 and tilt the switch to the position shown in Fig. 6, whereupon it may be immediately removed and a new switch quickly substituted, wired and put into commission in the reverse order of operation.

70

It will be seen that this construction and method of operation enables one to replace the switch with absolute minimum of labor and time whether the difficulty has been an electrical one involved in the switch per se, or mechanical in connection with the switch operating mechanism or the interlocking mechanism.

75

It will be particularly noted that this construction provides a means for mounting the entire mechanism of a quick-make, quick-break switch as well as a complete cover-interlocking mechanism upon a single removable frame or carrier member as a unit and that means are provided for accurately positioning the unit in the box for interlocking engagement with the pin or projection carried by the cover. This arrangement makes it possible to assemble and accurately adjust the units at the factory by expert workmen in such a manner that the switch units may be perfectly interchangeable with all switch boxes of the same catalog number and thus avoid the necessity of fitting or adjusting by a possibly inefficient wireman in the field.

80

I claim:

85

1. A switch box open at one side and having a hinged cover for the front, a removable switch unit comprising a base plate adapted to interlock with one wall of the box; and a side plate adapted to close the side of the box and to interlock with another wall of said box, and switch mechanism supported by the base plate and having actuating mechanism; and cooperating cover interlocking mechanism carried by the side plate.

90

2. A switch box open at the front and at one side and having a hinged cover for the front, a removable switch unit including a switch supporting frame having a tongue adapted to interlock with one wall of the box and having a side plate adapted to close the opening in the side of the box, and quick-break mechanism carried by the said frame and removable therewith.

95

3. A switch box having a hinged cover and having an opening in one of its walls, a removable switch unit independent of the box and the cover and including a base plate supported by the bottom of the box and adapted to interlock with one wall of the box, and a side plate adapted to close the opening in the wall of the box and to interlock with the wall of the box adjacent said opening, and switch mechanism carried by the base plate and having actuating mechanism carried by the side plate.

100

4. A switch box open at one side and hav-

105

- ing a hinged cover for the front, a removable switch unit including a switch frame adapted to interlock with two opposite side walls of the box and adapted to close the open side of the box, and switch mechanism supported by said frame and having actuating mechanism and a handle, said switch unit being removable as a completely assembled and adjusted unit.
10. 5. A switch box open at the front and at one side and having a hinged cover for the front hinged to one side of the box opposite the open side, a removable switch unit comprising a base plate adapted to interlock with a slot in one side of the box and having a side plate adapted to interlock with the opposite side of the box and to close the opening in the side of the box, and quick-break switch mechanism carried by the base plate and side plate and removable therewith.
15. 6. A switch box open at the front and at one side, a cover for the box, a removable switch unit comprising a base plate and an integral side plate adapted to cover the side opening of the box, switch mechanism supported by the base plate and interlocking means for securing said base plate and said side plate to the edges of the open side of the box, said unit being held in place by the cover of the box when it is closed.
20. 7. A switch construction comprising a box open at the front and having a cover hinged to one edge thereof, the side of the box opposite the edge to which the cover is hinged being cut away, a switch unit comprising a sheet metal carrier having a bottom plate and a side plate, switch contact members carried by said bottom plate, switch actuating means supported solely by said side plate, said bottom plate being provided at the side opposite said side plate with means for interlocking with the side of the box opposite the opening to permit said switch unit to be tilted when removing the switch unit and means for detachably connecting said side plate with the cut-away side of the box when the switch unit is in place.
25. 8. A switch construction comprising a box open at the front and provided with a cover hinged along one edge, the side of the box opposite the hinged edge of the cover being partly cut away, a removable switch unit having a side plate adapted to close the cut away portion in the side of the box and having tiltably releasable means of connection with the side of the box to which the cover is hinged, actuating mechanism for the switch carried by said side plate and including an external handle and quick make and break mechanism supported on the inside of said side plate and means for detachably securing said side plate to the edge of the cut away portion of the side of the box.
30. 9. A switch construction comprising a box open at the front and having a part of one side cut away, a cover hinged to the opposite side of the box, a readily detachable switch unit adapted to be detachably secured in the box and including a base plate having a tiltably means of connection with one side of the box and a side plate having a resilient, laterally movable portion provided with means for interlocking with the side of the box adjacent the cut away portion.
35. 10. A switch construction comprising a box having a cover hinged to one edge and a spring catch for the cover secured to the opposite edge of the box, the latter side of the box having a cut away portion, a detachable switch unit including a base plate having tiltably releasable means of connection with said box and a side plate for closing the cut away portion of the side of the box, said side plate being provided with interlocking means of connection with the edges of the cut away portion, actuating mechanism for the switch supported solely by said side plate and including quick make and break mechanism supported inside of the said side plate and cover interlocking mechanism supported solely by said side plate and co-acting with said actuating mechanism and adapted to releasably interlock with the cover of the box when the switch mechanism is in place and the cover is closed.
40. 11. An inclosed switch construction including a box having an opening in one of its side walls and a slot in its opposite side wall, a switch unit including a carrier having a bottom plate and a side plate, said bottom plate having a projecting portion for interlocking with the slot in the box and the side wall of said carrier being adapted to cover and to close the opening in the side wall of the box, a switch mounted on said carrier and including stationary and movable contacts and operating means for said movable contacts, the open side wall of the box having open ended screw receiving slots adjacent said opening and screws carried by said carrier for detachable engagement with said screw receiving slots.
45. 12. An inclosed switch construction including a box, a cover for said box, a switch frame having detachable interlocking engagement with opposite side walls of said box, a switch mounted on said frame and including actuating means together with cooperating means for detachable interlocking engagement with said cover when the switch is in closed position.
50. 13. An inclosed switch including a box having an opening in one of its walls, a cover hinged to said box, a switch frame having a tiltably detachable interlocking engagement with said box and having a projecting portion to close the opening in the wall of the box, a switch mounted on said frame as a unit and including actuating means and a co-acting spring pressed hook member for engagement.

with said cover when the switch is in closed position:

14. An inclosed switch construction including a box having an opening in one of its walls, a cover for said box, a readily detachable switch frame having interlocking engagement with one of the walls of said box and an integral portion adapted to close the opening in the wall of said box, a switch mounted on said frame together with an operating handle and a cooperating lever member adapted to lock said cover closed when the switch is on and to release said cover when the switch is off.
